UNITED STATES PATENT OFFICE

1,926,513

AUTOMATIC DAMPER REGULATOR

George F. Clamer, Collegeville, Pa.

Application August 21, 1931. Serial No. 558,553

2 Claims. (Cl. 137—153)

The herein described invention relates to automatic damper regulators in which the flow of air for combustion is admitted, when required for combustion by means of the various parts hereinafter particularly brought out through the medium of damper plate opening and closing member operated by medium of a valve, to sever and renew the communication between the source and the furnace intake when the air for combustion is not required on heating furnaces of steam, hot water, vapor, or hot air using coal, wood, gas, or oil fuel.

One of the objects of the invention is to provide a device to prevent cold air from entering the furnace after an automatic stop, of gas, coal, wood, or oil fired furnaces, and thereby preventing the surfaces of the interior of the furnace, which is primarily intended as heating surfaces, from being cooled during the stand by period, after the desired temperature has been reached, with the resultant saving of fuel of whatever sort used, and in an even temperature, and to provide the necessary draft for an increased temperature. Another object is to provide a device of few parts; no complicated movable parts, and of such design and construction as to be easily installed in any type of heating furnace irrespective as to the fuel used. A further object is to provide a device as hereinafter described which will be convenient in operation, inexpensive to manufacture, reliable in use, and of such nature as to enable anyone to operate the said device.

While the foregoing explains the general purpose and objects of the invention, other objects and advantages will appear in the specifications that follow, in which the novel features, construction and arrangement will be brought out, described and claimed.

In the accompanying drawing, and by reference, made a part of this specification, and in which corresponding parts are denoted by like designating numerals, is illustrated one form of the embodiments of the invention capable of carrying the same into practical operation, it being understood that the invention is not necessarily limited thereto, as various changes in shape, proportions, and general assemblage may be resorted to without departing from the principle of the invention, or sacrificing any of its advantages, in which, Figure 1 is a top view, partly in section; Figure 2 is a front view. To more fully describe the drawing and to make clear the operation and purposes of the herein described invention, the numeral 3 shows a housing or casing attached to the inlet side of the blower by means of screws or combined bracket, or other suitable and satis-

factory means. One method is illustrated by 3'. A conduit 4 leading from a supply of oil under pressure is connected with casing 3 by means of a coupling having a ball check valve 5 pressed to its seat by means of spring 6. It will be obvious by reference to the drawing that the oil pressure in casing 3 is controlled by check valve 5 so constructed that a slow flow from casing 3 to conduit 4 takes place to relieve the former of the pressure therein when the pressure in conduit 4 drops. Located in casing 3 is a bellows 8 responsive to the pressure therein. A stem 7 passes through casing 3. The free end of bellows 8 is connected with the upper end of stem 7 by means of a reduced portion that forms a shoulder. A spring 9 tending to normally expand the bellows surrounding stem 7. A yoke shaped lever 11 is pivoted at 10 on the lower part of casing 3. The lower end of stem 7 is provided with cross pin 15 upon which lever 11 rests intermediate its ends whereby it moves in response to pressure conditions in chamber 3. Between the arms of the yoke of lever 11 is a damper 13 pivotally mounted thereon by means of pins 12. Bolts 14 passing through over-sized apertures on diametrically opposed flanges on damper 13 are screw threaded on the inlet end 13' of the blower to serve as guides and limit the movement of the damper. The over-sized apertures for bolts 14 permit free tilting of damper 13 in operation.

In operation, in which is illustrated but one method for a mechanical controlled draft applied to a heating appliance showing damper attached to a blower, when a motor has been started, oil pressure to operate the parts in the casing, is supplied by a pump and through the line 4 giving movement to the ball check 5 pressing on the bellows and spring 6 to provide movement to the piston rod or arm 7 movably connected by a pin 15 to the arm 10' of the yoke shaped member 11 and through the free movement gives action thereto and thereby causes the top most position and the lower portion to work in unison away from the intake 13' in an angular movement. This movement is controlled by the bolts 14 adjustably secured to permit or cause one portion of the periphery of the damper plate to stop and the yoke arms continue to swing the opposite portion of the periphery of the damper plate in a slow angular movement assuming a position parallel with the inlet face of the blower, which regulates the exact draft required by the particular make of the furnace. After the correct amount of draft has been permitted to enter, the automatic shut off causes the yoke shaped member to cause

the draft damper plate to again close. When the damper plate has been opened the oil pressure, as supplied by the burner pump through the line 4 will be maintained as long as the burner pump operates. When the burner pump has stopped, the pressure will remain for some time in the housing, held there by the ball check which will permit the air of combustion to enter the fire pot for a period of time after the burner has stopped. This will permit the combustion of all fuel. As the oil slowly leaks past the ball check valve, in which the seat has been scored, the spring will cause the piston to pull on pin attached lever, with the damper plate attached as described, against the inlet port of the blower, thus preventing continuous inlet of cold air over the heating surface of the furnace, and effecting a saving of fuel by retaining the heat in the furnace. It is to be understood, that in showing and describing one method, that I do not confine myself to that particular form, but other methods can be adopted, as in the instant construction either a metal bellows, a metal diaphragm, a fabric diaphragm, or a solenoid coil, or an electro-magnet can be used for the motive power, and can be operated on oil burners either with air pressure, oil pressure or electrically, or a combination of the same.

For a gas fired boiler the use of electricity is preferred with a solenoid coil or magnet, but there may be used a diaphragm operated by gas pressure to open damper when starting, and close the same by means of a spring or weight during the standby period; and with the ball check preventing too quick a closing of the intake damper on the furnace. For mechanical coal burners, to prevent the continuous draft after blower has been automatically stopped which would cause over heating and waste of fuel, I prefer, but do not restrict myself, to the use of the device substantially as shown for operating the inlet damper of the blower using a solenoid coil in parallel or series with the electric circuit to the motor, so that on the starting of the motor the solenoid coil will push open the air inlet damper and compress the spring, and on the stopping will be demagnetized and the spring will close the damper at once, thereby

preventing to a large extent over-heating and the consistent saving of fuel by preventing the chimney draft continuing to "pull" the fire after an automatic shut down.

Having thus described my invention, what I claim as new and desire to secure by Letters Patent, is:—

1. In combination with a pipe adapted to be connected with the inlet of a blower, a damper, bolts for tiltably guiding and limiting the movements of said damper on the inlet end of said pipe, a casing providing a chamber, means for mounting said casing on said pipe, a lever pivotally mounted at one end on the lower portion of said casing, said damper being swingably mounted on the other end of said lever, metal bellows in said chamber, a stem connected with said bellows, said stem extending through the lower portion of said casing to cooperate with said lever intermediate its ends, a spring surrounding said stem tending to expand said bellows and close said damper, an inlet for said chamber adapted to be connected to a supply of fluid under pressure, a check valve on said second mentioned inlet and means on said check valve for slowly relieving the pressure in said chamber when pressure drops in said supply whereby to retard the closing of said damper. 90

2. In combination with a pipe adapted to be connected to the inlet of a blower, a damper, bolts for tiltably guiding and limiting the movements of said damper on the inlet end of said pipe, a casing providing a chamber, a lever pivotally mounted at one end on the lower part of said casing, said damper being swingably mounted at the opposite end of said lever, a metal bellows in said chamber, a stem connected with said bellows, said stem extending through the lower part of said casing to cooperate with said lever intermediate its ends; a spring surrounding said stem and tending to expand said bellows and close said damper, an inlet for said chamber adapted to be connected to a supply of fluid under pressure; a check valve in said inlet and means on said check valve for slowly relieving the pressure in said chamber upon a drop of pressure in said supply whereby closing of the damper is retarded. 110
